WALTER E. OLIVER, OF PROVIDENCE, RHODE ISLAND, ASSIGNOR TO PARK BROS. & ROGERS, OF PROVIDENCE, RHODE ISLAND, A COPARTNERSHIP.

SUPPORT FOR SOFT COLLARS.

1,123,573.

Specification of Letters Patent.

Patented Jan. 5, 1915.

Application filed May 24, 1911. Serial No. 629,187.

To all whom it may concern:

Be it known that I, WALTER E. OLIVER, a citizen of the United States, and resident of Providence, Providence county, State of Rhode Island, have invented certain new and useful Improvements in Supports for Soft Collars, of which the following is a specification.

This invention relates to a link and support for the front of a soft collar.

It is well known that a soft collar, when in use, becomes depressed and crumpled at the front and consequently more or less unsightly.

The object of this invention is to provide a device which will overcome these disadvantages and at the same time be simple, convenient, and almost wholly concealed in the folds of the collar.

The novel features of the invention will be apparent from the following description taken in connection with the accompanying drawings.

In the drawings: Figure 1 is a front view of a portion of a collar showing one embodiment of my invention; Fig. 2 is a perspective of the link and support shown in Fig. 1; Fig. 3 is a view similar to Fig. 1 but showing another embodiment of my invention; Figs. 4 and 5 are perspective views of still other embodiments of my invention; Fig. 6 shows a modification of Fig. 1 in which the uprights are bowed; Fig. 7 is a top edge view of the support shown in Fig. 2.

Throughout the several views the corresponding parts are designated by the same reference numerals.

Numerals 10 indicates a collar of the usual construction, having buttons 11 and 12 for holding the ends in proper position, the button 11 engaging the shirt whereby the front of the collar is held thereon. Between the folds of the collar I provide a support 45 comprising a U-shaped body having upright members 13 and a cross member 14 connecting the uprights. At the upper end of the upright members 13 I may provide lateral extensions 15. These lateral extensions are preferably curved rearwardly so as to conform to the shape of the collar when worn. The upper edge of the support, as thus formed, engages the underside of the collar at the point of folding. At the lower 55 end of each of the uprights 13 I provide a

button 16 which engages one of the button-holes 17 in the outer fold of the collar whereby the uprights 13 serve to prevent the collar from crumpling at the front and serves as a link to connect the lower corners 60 of the outer fold of the collar, thereby taking the place of the usual link employed for this purpose.

Figs. 1 and 2 illustrate the preferred form of my invention. In this case the cross member 14 connects the lower ends of the upright members at points adjacent the buttons 16 and thereby prevents the uprights from being bent by an excessive lateral pull on the buttons 16. In this form the necktie 70 may be placed either in front of or behind the cross member 14.

In the form shown in Fig. 3 the cross member 14 is placed at the top of the upright members 13. This form is particularly adapted for collars having upper corners which fit closely together, as the cross member is almost wholly concealed and a free space is left for the necktie.

Fig. 4 shows a form similar to that shown 80 in Figs. 1 and 2, in which the support is made of wire, hooks being provided instead of the buttons 16.

Fig. 5 shows a Y-shaped form in which a single upright member 18 extends from a cross member 14 to which the buttons 16 are secured, this upright having branches 85 13 formed with lateral extensions 15 for supporting the collar.

I prefer to make the support of sheet 90 metal but it will be understood that other materials, as for example celluloid, may be used. It will also be understood that various changes may be made in the forms of construction shown without departing from 95 the spirit of my invention and I therefore do not wish to be limited to the precise forms shown and described.

What I claim is:

1. A device of the class described, constructed of thin sheet metal and comprising upright members having lateral extensions at the upper ends thereof, a button secured to the lower end of each of said upright members and a cross member connecting said upright members.

2. A device of the class described, having a body constructed of thin sheet metal and adapted to lie between the folds of a collar at the front thereof, said body comprising 110

upright members having their lower ends connected, the upper ends of said upright members having lateral extensions adapted to support the upper edge of the collar, and buttons secured to the lower ends of said upright members and adapted to engage the outer fold of the collar.

3. A unitary device for supporting soft collars, comprising two spaced forwardly 10 extending projections adapted to engage openings in the lower margin of the ends of the outer fold of the collar, two laterally extending portions adapted to lie between the folds of the collar and support 15 its top edge, and intermediate upright members and a cross member permanently connecting and spacing the said projections and laterally extending portions.

4. In a combined double collar button and support, a pair of supporting members, collar buttons secured to the lower ends thereof, and means for maintaining said members in spaced relationship to each other.

5. A device of the class described, con-

structed of thin sheet material and comprising upright members having lateral extensions at the upper ends thereof, a button secured to the lower end of each of said upright members and a cross member connecting said upright members. 25 30

6. A device of the class described having a body constructed of thin sheet material and adapted to lie between the folds of a collar at the front thereof, said body comprising upright members having their lower 35 ends connected, the upper ends of said upright members having lateral extensions adapted to support the upper edge of the collar, and buttons secured to the lower ends of said upright members and adapted to 40 engage the outer fold of the collar.

In testimony whereof I affix my signature in presence of two witnesses.

WALTER E. OLIVER.
